O. WOERNER.
RETAINING FORM,
APPLICATION FILED APR. 1, 1918.

1,278,545.

Patented Sept. 10, 1918.

Inventor:
Otto Woerner
By Chas. N. Hustler
Attorney.

UNITED STATES PATENT OFFICE.

OTTO WOERNER, OF EAST LANSDOWNE, PENNSYLVANIA.

RETAINING-FORM.

1,278,545.

Specification of Letters Patent. Patented Sept. 10, 1918.

Application filed April 1, 1918. Serial No. 225,920.

To all whom it may concern:

Be it known that I, OTTO WOERNER, a citizen of the United States, residing at East Lansdowne, Delaware county, State of Pennsylvania, have invented a new and useful Retaining-Form, of which the following is a specification.

My improved retaining form is a collapsible device adapted to be held erected in a box for containing articles such as hose and to be used for keeping the hose in place in the box. It is designed to provide simple, inexpensive, convenient and efficient means for holding articles in desired positions and relations.

In the drawings, Figure 1 is a collapsed form made in accordance with my invention; Fig. 2 is a perspective view of the erected form, and Fig. 3 is a plan view of a box containing the erected form and hose held thereby.

The form illustrated in the drawings comprises the rectangular body 1, preferably cut from paper board, provided with the part 2 cut diagonally therefrom along the irregular line 3 and hinged thereto along the score line 4, the part 2 being provided with the transverse scores 5 and 6, whereby such part is adapted to be erected on the body with its sections 2^a, 2^b and 2^c extending transversely with respect to each other in braced relation to form an end rest.

The body 1 is provided with the further parts 7, formed longitudinally therein, hinged thereto along the respective score lines 8, separated therefrom along the irregular lines 9 and 10, and separated from each other along the line 11, the parts 7 being provided with the transverse scores 12 and 13 dividing them into sections 7^a, 7^b and 7^c. The parts 7 are thereby adapted to be erected to form side rests on the body, with the sections 7^a directly connected thereto and extending lengthwise thereof, the sections 7^b turned back on the score lines 12 to a bracing position on the body transverse to the sections 7^a, and the sections 7^c turned back on the score lines 13 to a bracing position transverse to the section 7^a.

The body 1 is provided with the further part 14 extending across its end adjacent to the sections 7^c and around such sections to score lines 15 which are a continuation of the score lines 13, the part 14 being adapted

to keep the body proper from spreading and to be erected by turning it on the score lines 15.

A box 16, of rectangular form, receives the form, which is cut to the desired size for the function required. The sections 2^a and 2^b are erected to form a substantially V-shaped rest with its apex in the longitudinal center of the box and its section 2^c resting against an end 16^a of the box. The sections 7^a are erected and held in position by the sections 7^b and 7^c, which are turned to a position of rest on the bottom of the box between the sections 7^a and the sides 16^b of the box against which they bear, the part 14 being turned up and bearing against the end 16^a of the box.

Half hose 17 are placed in the box with the heels 17^a of the alternate pairs placed alternately on opposite sides of the V-shaped support 2^a—2^b and with the contracted tops 17^b placed between the parts 7^a, whereby such hose are held in proper position and relation.

The term body as used in the claims is to be understood as meaning the main part of the structure as distinguished from and not including the hinged members erected thereon.

Having described my invention, I claim:

1. A form comprising a flat body having a collapsible end rest of substantially V-shaped form and collapsible side rests extending longitudinally of said body, said rests being cut from said body and hinged thereto within the edges thereof. 90

2. A form comprising a body having a part cut diagonally therefrom within its edges and hinged thereto on a diagonal line, said part being creased to form sections adapted to stand on said body in transverse relation, and said body having further parts cut longitudinally therefrom and hinged thereto on longitudinal lines, said parts last named being creased to form sections adapted to stand on said body in transverse relation. 100

3. A form comprising an approximately rectangular body having a part cut diagonally in an end thereof within its edges and hinged thereto on a diagonal line, said part being scored to provide sections adapted to stand in transverse relations, and said body having parts cut therein and hinged on lon-

itudinal lines thereof, said parts last named being scored to provide sections adapted to stand in transverse relation.

4. A form comprising a body having collapsible parts cut therefrom and forming side rests hinged on longitudinal lines within the edges thereof, said parts having scores forming sections adapted to be turned back and stand on said body, and a part connecting separated sides of said body to which said rests are hinged.

5. The combination with a body having collapsible end and side rests hinged thereto within the edges thereof, said rests hav-

ing transverse members adapted to stand on 15 said body, and a part hinged to separated sides of said body to which said side rests are hinged.

6. The combination with a box, of a collapsible form made from an approximately 20 rectangular blank and adapted to be inserted in said box, said form comprising a flat body and collapsible rests cut therefrom and adapted to be erected and supported in said box for holding articles therein.

In testimony whereof I have hereunto set my name this 23rd day of March, 1918.

OTTO WOERNER.
